R. S. O'NEIL,
CONTACT OF ELECTRICAL SWITCH GEARS,
APPLICATION FILED JAN. 24, 1920.

Patented Sept. 7, 1920.

-FIG. I.

-FIG. 2.

—FIG. 3.—

Rudolph Stuart O'Neil

By John G. Lamb Inventor

UNITED STATES PATENT OFFICE.

RODOLPH STUART O'NEIL, OF LONDON, ENGLAND, ASSIGNOR TO O'NEIL'S RECORDER
SYNDICATE LIMITED, OF LONDON, ENGLAND.

CONTACT OF ELECTRICAL-SWITCH GEARS.

1,351,963.

Specification of Letters Patent.

Patented Sept. 7, 1920.

Application filed January 24, 1920. Serial No. 353,764.

To all whom it may concern:

Be it known that I, RODOLPH STUART O'NEIL, a subject of the King of Great Britain, residing at London, England, have invented certain new and useful Improvements in and Connected with the Contacts of Electrical-Switch Gears, of which the following is a specification.

In electrical switch gear, it is in many instances necessary or desirable to locate a contact in a particular position relatively to some other member of the switch mechanism, or where a plurality of contacts are employed to be able with convenience to change or vary the order of the contacts and their relative distances apart, and it is particularly desirable that such changes can be easily and quickly made, while at the same time utilizing a construction which is simple and cheap to manufacture.

The object therefore of the present invention is to attain these desired ends, and the invention deals with a switch device in which certain of the members hereafter described are of circular formation.

The invention primarily consists in constructing each contact member so that it is adapted to be clamped between a pair of rings which are in opposed relation to each other, and whereby, prior to the clamping together of the rings, the contacts can be adjusted in position in circumferential directions around the said rings, and the rings can then again be clamped together to retain the contact members in position.

Dealing more specifically with the construction of the invention, each contact member is located in a carrying block, and the blocks are located between the opposed supporting rings, the facing surfaces of which are shaped to form guides to retain the blocks in position during their adjustment in circumferential directions, as for example the opposed faces of the supporting rings may be V-shaped, in which case the upper and lower faces of the blocks would be correspondingly V-shaped.

In carrying out the invention the contact members or brushes proper are passed freely through apertures in the blocks, and the

said brushes are maintained in an engaging position with say a revoluble member located within the clamping rings and movable about a pivot coaxial with the rings, the contact brushes being maintained in frictional contact with the inner member by means of springs acting on the outer ends of the contact members, or by spring-actuated levers or the like acting thereon.

In such an arrangement the contact carrying blocks are conveniently insulated from the clamping rings, and the electric current passes through the inner revoluble member from which the current passes to the contact brushes as the said inner member is revolved.

The invention will be further described with reference to the accompanying drawings, whereon Figure 1 is a central vertical section, and Fig. 2 is a plan view, of a switch constructed according to this invention, the plan view at Fig. 2 having the cover removed. Fig. 3 is a detail view on a larger scale in vertical section showing one of the contact brushes and its carrying block.

Referring to the accompanying drawings, each contact brush 1 passes with a sliding fit through a carrying block 2, the upper and lower surfaces of the block 2 in the construction now being described being V-shaped. The carrying blocks 2, a plurality of which are fitted in the construction shown, are located between a lower ring 3, which may be formed if so desired integral with the base 4 of the case, and an upper ring 5, the facing surfaces of the rings 3 and 5 being shaped to conform with the blocks 2.

The blocks 2 having been placed in the desired relative positions between the rings 3 and 5, spacing pieces 6 are placed in required positions between the rings 3 and 5, and the upper ring 5 is clamped down upon the lower ring 3 by clamping screws 7, Fig. 2.

The carrying blocks 2 are insulated from the rings 3 and 5 by strips or plates 8 of insulating material, such as mica. It will now be understood that by releasing the

upper ring 5 the carrying blocks 2 can be arranged at any required distance apart circumferentially between the rings, and the upper ring can then be clamped again in position.

In the switch illustrated a revoluble member is located within the clamping rings 3 and 5 and is mounted upon a revoluble spindle 9, the revoluble member comprising a flanged outer ring 10 connected by arms 11 to a hub 12, which hub is clamped between upper and lower disks 13, which latter are keyed upon the spindle 9, insulating material 14 being inserted between the hub 12 and the disks 13.

The flanged ring 10 of the revoluble member carries a conducting ring 15, shown in dotted lines at Fig. 2, having a tongue 16 (or a plurality of tongues) extending to the periphery of the flange of the ring 10, the tongue 16 being in the plane of the contact brushes 1 and in electrical contact with the ring 10.

The ring 10 also carries an electrically conducting ring 17 which is in electrical contact with the ring 10, and 18 represents insulating distancing material, the ring 17, the ring 15 and the insulating material being all clamped to the flange of the ring 10 by bolts as shown.

At one part around the circumference of the upper ring 5 a block is fixed to the said upper ring, through which block is fitted a freely sliding brush 19, the block being insulated from the upper ring 5, and the brush 19 is held in contact with the electrically conducting ring 17 by means of a spring-actuated lever 20, an electrical conductor 21 supplying current to the brush 19 through the block in which the brush slides.

It is essential in such a construction as now described, that the contact brushes 1 should be maintained in pressure contact with the periphery of the revoluble member, that is to say with the periphery of the insulating material 18 and the end of the tongue 16, and any suitable means may be employed to this end, that is each block might be fitted with a spring-actuated lever, such as 20, to act on the end of the contact brush 1 carried by the block, but in the example shown in the drawing the block 2 is formed with an extended sleeve 2^x having a closure cap as shown at Fig. 3, and a spring within the sleeve acting between the cap and the end of the brush 1. The cap may form a means by which a flexible electric conductor can be connected to the sleeve 2^x, and the contact brush 1 is always maintained with its end pressed against the periphery of the revoluble member, while at the same time it can be adjusted when desired, as regards position, between the upper and lower clamping rings 3.

The example of construction illustrates

the device as inclosed in a circular case 22 and having a top cover 23 in which is formed the bearing for the upper end of the spindle 9.

In a suitable position within the apparatus is fitted a conductor distributing plate 24, through which the electrical conductors which may pass into the apparatus through an aperture 25 in the cover 23, Fig. 1, may pass, the conductor 21 by which the current passes into the apparatus passing through the aperture 26, Fig. 2, in the plate 24, while the flexible conductors from the brushes pass through the remaining apertures in the plate 24.

The spindle 9 may be fitted with a lever 27 or any other suitable device by which revolution or angular adjustment may be communicated to the revoluble member about the axis of the spindle 9.

With the construction described it will now be understood that the current passes by the brush 19 to the flanged ring 10 and consequently to the conducting ring 15 which is in electrical contact therewith, and as the revoluble member receives motion about the axis of the spindle 9, current will be conveyed to one or other of the plurality of contact brushes 1 as the tongue 16 of the ring 15 passes in contact with the ends of the said brushes. If therefore the brushes are set at regular distances apart for example, and the revoluble member receives revolution at a uniform speed, the current will pass through the contact brushes in regular succession, all according to the arrangement of the brushes.

Incidentally this switch provides a cheap and convenient arrangement by which the contacts can be varied in relative position as required, and in which any arrangement of contacts can be built-up, and since the rings and the blocks can be made in standard sizes, such may be made up for stock and assembled in any desired manner according to requirements.

What I claim as my invention and desire to secure by Letters Patent is:—

1. An electrical switch device; comprising in combination a pair of clamping rings in opposed relation to each other, a plurality of separate electrical contact members located between said rings, insulated therefrom, and adjustable in position in circumferential directions between said rings, and means for clamping said rings together to retain said contact members in the positions in which they have been placed.

2. An electrical switch device; comprising in combination a pair of clamping rings in opposed relation to each other, a plurality of separate electrical contact members located and adjustable in position in circumferential direction between said rings and insulated therefrom, means for clamp-

- ing said rings together to clamp said contact members in the positions in which they are placed, a central revolute spindle, a concentric revolute member located within 5 said clamping rings fixed to said spindle and insulated therefrom, means for supplying electric current to said revolute member, a tongue extending from said revolute member and adapted to contact in succession with said separate electrical contact members located between said clamping rings as said revolute member is revolved, and an electric conductor from each of said electrical contact members located 10 15 20 25 30 35 40 45 50 55 60 65 70 75 80 85 90 95 100 105 110 115 120 125 130
- material carried by said revolute member, a radial tongue extending from said conducting ring to the periphery of said ring of insulating material to contact in succession with said stationary brushes carried by said clamping rings as said revolute member receives angular motion about its axis, and an electric conductor from each of said electrical contact members located between said clamping rings to convey the current therefrom to the points required.
5. An electrical switch device; comprising in combination a pair of clamping rings in opposed relation to each other, a plurality of separate carrying blocks located and adjustable in position in circumferential direction between said rings and insulated therefrom, a radial inwardly sliding contact brush carried by each of said carrying blocks, means for forcing each brush radially inward relatively to its carrying block, means for clamping said clamping rings together to hold said blocks in position, a central revolute spindle, a concentric revolute member located within said clamping rings fixed to said spindle and insulated therefrom, means for supplying electric current to said revolute member, an insulating ring carried by said revolute member, a tongue in electrical connection with said revolute member extending to the periphery of said ring of insulating material and adapted to contact in succession with said contact brushes carried by said blocks between said clamping rings as said revolute member is revolved, and an electric conductor from each of said carrying blocks located between said clamping rings to convey the current therefrom to the points required.
6. An electric switch device; comprising in combination a case, a clamping ring on the base of said case within the interior thereof, a second clamping ring in opposed relation to the first fixed clamping ring, a plurality of separate electrical contact members located and adjustable in position in circumferential direction between said rings and insulated therefrom, means for clamping the rings together to hold said contact members in position between them, bearings in the case concentric with said clamping rings, a central revolute spindle carried in said bearings, a concentric revolute member fixed to said spindle and insulated therefrom, a contact brush carried by one of said clamping rings and contacting with said revolute member to convey electric current thereto, means for connecting said brush with a source of electric current, a conducting ring carried by said revolute member and in electrical contact therewith, an external ring of insulating

stationary brushes carried by said clamping rings as said revoluble member receives angular motion about its axis, and an electric conductor from each of said electrical contact members located between said clamping rings to convey the current therefrom to the points required.

In testimony whereof I have hereunto set my hand in the presence of two witnesses.

RODOLPH STUART O'NEIL.
